UNITED STATES PATENT OFFICE.

FREDERIC S. THORNLEY, OF PIERRE, SOUTH DAKOTA, ASSIGNOR OF
ONE-HALF TO W. S. LITTLE, OF PIERRE, SOUTH DAKOTA.

KEY-ARRESTER MECHANISM.

No. 832,938.

Specification of Letters Patent.

Patented Oct. 9, 1906.

Original application filed May 5, 1905, Serial No. 269,476. Divided and this application filed July 8, 1905, Serial No. 269,114.

To all whom it may concern:

Be it known that I, FREDERIC S. THORNLEY, a citizen of the United States of America, and a resident of Pierre, Hughes county, 5 South Dakota, have invented a new and useful Key-Arrester Mechanism, of which the following is a specification.

This application is a division of my application for Letters Patent of the United 10 States, filed May 5, 1905, serially numbered 259,476, for voting-machine.

This invention relates to voting-machines, and has for its object to provide an improved key - arrester mechanism whereby various 15 vote-indicating keys or devices may operate when moved to voted position to prevent movement of various other keys and devices.

My invention consists in the construction, arrangement, and combination of elements 20 hereinafter set forth, pointed out in my claims, and illustrated by the accompanying drawings, in which—

Figure 1 is a rear elevation of a voting-machine involving my improvement, the 25 rear door or closing-plate being removed. Figs. 2 and 3 are detail elevations of two forms of mechanism constituting my improvement, and Figs. 4 and 5 are cross-sections of the same. Figs. 6 and 7 are detail 30 views illustrating the key-bars and connections.

In a general way my improved voting-machine is constructed of a casing adapted to contain and support various operating 35 devices, and parts of said casing are herein shown and comprise a bottom plate 10, end plates 11 12, a top plate 14, and a vertical partition-plate 16. A plurality of arbors 18 are arranged in a vertical row near the end 40 plate 11 of the casing and are journaled for oscillation in the partition-plate 16. Straight-ticket keys are mounted on the arbors 18 and are adapted for manual oscillation to move said arbors, which in turn move ticket-bars, 45 as set forth in the parent application, and are moved back to initial position by said bars.

A plurality of candidate-keys 20 are provided, one key for each candidate to be voted for on the machine, and said keys are arranged 50 in horizontal rows throughout each of the tickets in the planes of the straight-ticket keys and also are arranged in vertical rows in respect of the offices to be filled by the respective candidates. The keys 20 are

journaled by means of shafts or arbors 21, 55 mounted for oscillation in the partition-plate 16, and said keys extend approximately horizontally toward the straight-ticket keys normally. Arms 22 are mounted rigidly on and extend obliquely downward from the 60 shafts or arbors 21 and move through arcs in the oscillation of said shafts. Referring to Flg. 4, it will be observed that a shoulder 23 is fixed to each of the arbors 21, and a spring 24 is mounted between and impinges 65 said shoulder and the partition-plate 16. It is the function of the springs 24 to hold the keys 20 and their arbors in whatever position they may be placed manually. Straight-ticket bars 25, one for each mechanically- 70 voted ticket, are mounted parallel with each other in horizontal planes and are arranged for reciprocation in slide-bearings fixed to the front face of the partition-plate 16. Each of the ticket-bars 25 is arranged immediately 75 below a ticket row of keys. The straight-ticket keys are provided with arms 19, adapted to engage studs 27 on the ticket-bars 25, to move said bars toward the end plate 12. Studs 28 and 29 are formed on or fixed to 80 the bars 25 and project horizontally forward and are adapted to engage the arms 22 and oscillate the arbors 21 and keys 20 in one direction. The studs 28 serve the additional purpose of preventing movement of the 85 arms 19 beyond the studs 27. The studs 29 serve the additional purpose of engaging opposite faces of adjacent arms 22 and oscillating the arbors 21 and keys 20 in the opposite direction at times, and to this end an extra stud 90 29 is provided at the extreme right of each ticket row. Stops 30 are mounted in and project horizontally forward from the partition-plate 16 adjacent each key 20 and are adapted to engage and stop the rearward movement of 95 the arms 22, and thereby determine the degree of oscillation of the arbors 21 and keys in one direction. Links 31 are pivotally supported on and extend through slots 32 in the partition-plate 16, and said links are drawn in one direction by springs 33. The links 31 extend across end portions of the bars 25 and serve to move said bars to the left after said bars have been moved to the right by manual force applied to the straight-ticket keys. 100

A locking device is provided for each row of single candidates and is constructed as follows: A plurality of plates 44 are mounted 105

for vertical reciprocation in bearings on the rear face of the partition-plate 16 and engage each other end to end. Notches 45 are formed in the lower ends of the plates 44 to receive blades 46 on the arbors 21, and downward movement of said plates is prevented by engagement with said blades. Upward movement of one, another, or all of the plates 44 is permitted to the extent of one-half of 5 the width of either of the blades, and no more, further movement being prevented by engagement of the upper end of the upper plate with a stop or by engagement of another of the plates with a blade. The blades 10 46 project laterally equal distances from the centers of the arbors 21, and wings 47 are formed on and extend laterally from the outer end portions of said blades beyond the rear faces of the plates 44. When either of 15 the keys 20 of a single-candidate row is moved into voting position, either by voting a straight ticket or by voting a single key after scratching, the blade 46 on the moved key-arbor turns into the position shown by 20 dotted lines in Fig. 2, with its width interposed between plates 44. Such turning of the blade lifts the plate or plates 44 above it to the limit of upward movement, and in its new position said blade prevents elevation of 25 a plate 44 below it and prevents depression of the plates above it. By preventing depression of the plates above it the turned blade also prevents turning of another blade above it and by locking the plate or plates 30 below prevents turning of a blade in a lower plane in the same candidate row. Thus the turning of either single-candidate key into "voted" position effectually locks the remaining keys in the same candidate row. 35 A locking device is provided for each group of plural candidates (where two or more candidate-rows are grouped together in order that an elector may vote for more than one candidate) and is constructed as follows: A 40 spring 48 is anchored at one end, in this instance on a yoke 49, incapable of further downward movement, and then follows a sinuous course adjacent to blades 46^a on the arbors of two or more rows of keys 20 and is 45 adjustably anchored at its opposite end, in this instance by a screw 50 traversing a lug 51 on the plate 16. In this instance the blades 46^a are arranged at right angles to the positions of the blades 46 and normally occupy planes parallel with the spring 48. There is sufficient slack between the ends of 50 the spring 48 to permit just the desired number of keys to be turned and turn the desired number of blades 46^a, (dotted lines, 55 Fig. 3,) to flex the spring slightly from its true course. The spring is confined against lateral movement at points between the blades 46^a by bearings 52, fixed to the plate 16, and the flexing of said spring between 60 said bearings applies such tensile strain to

the spring as to prevent turning of either of the other blades. Wings 47^a are formed on and extend laterally from and at right angles to the blades 46^a at the rear of the spring 48. Recording-bars 53 are mounted for reciprocation in bearings 54, fixed to the rear face of the plate 16. The recording-bars 53 are parallel with and spaced apart from the plate 16, and one of such bars is provided for each ticket. The recording-bars 53 are pivotally 70 connected to the short arms of the pawls 35 by means of a rod 55. Vote-registers 56 (illustrated in conventional form in Fig. 1) are mounted on the recording-bars 53, and one of said registers is provided for each of 80 the candidates. The operation of turning the keys 20 into voted positions moves the wings 47 47^a into the path of travel of the vote-registers 56, and in the further operation of the machine said vote-registers are carried laterally by the recording-bars 53 and caused 85 to engage with and be moved rotatably by said wings.

In some localities and on some occasions all electors are not qualified to vote on all 90 candidates or questions, and I have made provision for locking all voting devices for questions and candidates as to which an elector is disqualified, as follows: A plurality of bell-crank levers 82 83 are provided and 95 are fulcrumed on the plate 16. Each of the levers 82 83 is formed with a long arm extending across the path of travel of removable and replaceable studs 84 in a locking-bar 85, mounted for rectilinear reciprocation 100 on the plate 16. Each of the levers 82 is formed with a short arm adapted to engage the lower end of the lowermost plate 44 of a vertical row of such plates and lift them into 105 such position that neither of the candidate-keys or independent keys of such row may be moved to voted position. Each of the levers 83 is formed with a short arm engaging and controlling a block 86, whereby strain may be applied to exhaust the slack of a locking-spring 48 and prevent the movement of any 110 group-key controlled by said spring into voted position. A plurality of levers 87 of the second class are fulcrumed at their lower ends on the plate 16 and extend upward 115 across the horizontal plane of the row of question-keys 80 81 and have their upper end portions crossing the path of travel of studs 88, removably and replaceably mounted in the locking-bar 85. A rock-shaft 89 is 120 mounted for oscillation parallel with the shaft 34 in bearings fixed to the plate 16, and is connected by a crank-arm 90 thereon to one end of the locking-bar 85. A retractile coil-spring 91 connects one end of the locking-bar 85 to the plate 16. The rock-shaft 125 89 is arranged to be oscillated by booth mechanism, as explained in the companion application of which this is a division. Partially-disqualified electors on entering the 130

5 booth oscillate the rock-shaft 89 and crank-arm 90, which actuates the locking-bar toward the right and causes studs 84 88 to engage levers 82, 83, and 87 and put said levers in such positions as will lock the plates 44 and springs 48 against such candidates and questions as come within the disqualification. After voting this elector returns as he came, and the spring 91 returns the locking-bar 85 to normal position and releases the levers 82, 83, and 87 from the influence of the studs 84 and 88.

I claim as my invention—

1. In a voting-machine, a series of party 15 rows of keys, each party row containing a straight-ticket key and candidate-keys, a bar mounted for reciprocation, a stud on said bar adapted to be engaged by said straight-ticket key, studs on said bar adapted to engage and move said candidate-keys in each direction dependent on the movement of said bar, a series of locking-plates arranged for reciprocation at right angles to said bar, said locking-plates in abutting contact with each other and having equal range of movement, each locking-plate formed with a notch in one end to receive a candidate-key, and a blade on each candidate-key and adapted to turn with said key in a notch 25 between pairs of said locking-plates and exhaust the range of movement of all the plates.
2. In a voting-machine, a series of rows of candidate-keys mounted for individual rotation in a fixed plate, blades on said keys, a 30 series of rows of locking-plates mounted for reciprocation at right angles to the rows of candidate-keys, the plates in each row abutting each other and having equal range of movement, each plate formed with a notch 35 to receive the blade of a candidate-key, bars

40 mounted for reciprocation, studs on said bars adapted to engage and move said candidate-keys rotatably in opposite directions, straight-ticket keys adapted to move said bars in one direction to turn said blades between pairs of locking-plates and exhaust the range of movement of all the plates, and springs to move said bars in reverse directions.

3. In a voting-machine, a series of rows of candidate-keys mounted for individual rotation in a fixed plate, blades on said keys, a series of rows of locking-plates mounted for reciprocation at right angles to the rows of candidate-keys, the plates in each row abutting each other and having equal range of movement, each plate formed with a notch to receive the blade of a candidate-key, bars mounted for reciprocation, studs on said bars adapted to engage and move said candidate-keys rotatably in opposite directions, straight-ticket keys adapted to move said bars in one direction to turn said blades between pairs of locking-plates and exhaust the range of movement of all the plates, 55 springs adapted to move said bars in reverse directions, levers adapted to engage and move individuals of the rows of plates and exhaust the range of movement of all the plates, a bar mounted for reciprocation and studs removably and replaceably mounted in said bar and adapted to engage and move said levers.

Signed by me at Pierre, South Dakota, this 3d day of July, 1905.

FREDERIC S. THORNLEY.
